UNITED STATES PATENT OFFICE.

JESSE LOWE, SR., OF BEARDSTOWN, ILLINOIS.

RESERVOIR AND METHOD OF ITS CONSTRUCTION.

1,159,055.

Specification of Letters Patent.

Patented Nov. 2, 1915.

Application filed January 29, 1915. Serial No. 5,031.

To all whom it may concern:

Be it known that I, JESSE LOWE, Sr., a citizen of the United States, residing at Beardstown, in the county of Cass and State of Illinois, have invented certain new and useful Improvements in Reservoirs and Methods of Their Construction, of which the following is a specification.

This invention relates particularly to the method of construction, as well as to the construction and arrangement, of reservoirs intended for receiving and holding water for use in houses and buildings of rural and farming communities, factories, railroad watering stations, stock feeding yards, towns, cities, in water power development and in mines, and has for its purpose the provision of a simple, effective and economical reservoir.

Other features and objects of the invention will be set forth in the following specification taken with the accompanying drawings, in which,—

Figure 1 is a plan view of a reservoir constructed in accordance with my invention as viewed from above; Fig. 2 is an enlarged sectional view taken on the line 2—2 of Fig. 1, looking in the direction of the arrow; Fig. 3 is a horizontal sectional view through one form of piling which may be used in constructing my reservoir; Fig. 4 is an enlarged vertical, sectional view through the valley, taken on the line 4—4 of Fig. 1, looking in the direction of the arrows, certain features of my construction being shown in elevation; Fig. 5 is a horizontal sectional view showing another form of piling which may be used in constructing my improved reservoir; and, Fig. 6 is an enlarged, transverse, sectional view through the water screen of my construction.

In the art to which this invention relates, it is highly desirable to obtain the desired supply of water as free as possible from surface and other impurities. The invention is peculiarly applicable to rural communities and water supplies needed in isolated localities, those generally speaking in the great farming States, the mountainous or hilly regions and along the line of railroads between large supply stations, where the topographical arrangement is such that water usually flows along by way of shallow val-

leys and through gravel beds or other water-bearing strata located underground some 55 distance below the surface. The accumulation of this water flowing through such strata or deposits is very desirable, and to provide a reservoir in which it may be received and stored, and be at the same time 60 protected from the surface water, is the principal object of this invention.

In constructing a reservoir in accordance with my invention, I first preferably seek a suitable location in a valley 10, located between the corresponding elevations 11. Fig. 1 shows this valley in a purely technical manner for purposes of illustration, and it is not intended in any way as a limitation as to the use of my improvements in any 70 location in which they may be found particularly applicable.

After the desired location and size of reservoir have been determined upon, a series of sheet piling 12 is driven into the ground 75 to the desired depth, as shown in Figs. 2 and 4, to inclose a space 13 of the required dimensions. I also drive two series of sheet piling, extending outwardly across the valley from each side of the inclosing sheet 80 piling 12, to form wing walls 14 which are preferably continuous with that wall of the inclosure 13 which is farther down the valley, as shown in Figs. 1 and 4. This piling is driven through the upper stratum of earth 85 15, through the gravel or other water-bearing stratum 16, and some distance farther into the lower stratum of clay, rock, or loam 17.

The piling used in inclosing the space 13 90 and in constructing the wing walls 14 is of a sheet metal form well known, preferably the form of piling shown particularly in Fig. 5. This piling consists of a series of separate piles 18^a and 18^b which are arranged alternately, and which interlock with each other along their vertical edges when driven. Each pile 18^a is of channel form, and adjacent each flange of the pile and projecting outwardly from the web of the pile in the 100 same direction as the flange, is a Z-bar 18^c which is riveted or otherwise secured to the pile before it is driven, thus forming a space 18^d between the flange of the pile 18^a and the Z-bar 18^c secured thereto. The other 105 complementary pile 18^b is also of channel

form, and is so arranged that when driven the flanges thereof project into the spaces 18^a formed between the jaws along the lateral edges of the piles 18^a. With this construction it will be seen that as the piles are driven the earth will enter the unoccupied portions of the spaces 18^a so as to tightly calk the joints along the vertical edges of the piling and substantially prevent leakage of water therethrough.

In Fig. 3 I have shown another form of metal piling which may also be used in constructing my improved reservoir. This piling consists of a series of separate piles 19, each having a pair of jaws 19^a along one edge thereof and an enlarged head or flange 19^b along the other edge thereof. When the piles are driven the enlarged flanges 19^b are adapted to enter the spaces 19^c between the jaws 19^a, and the earth will enter the unoccupied portions of these spaces to tightly calk the joints, as in the use of the other form of piling above described. It will be understood that other suitable forms of piling may be used, if desired.

The inclosing sheet piling 12, as above described, is preferably driven into the ground in the shape of a rectangle extending downwardly through the gravel or water-bearing deposit, as shown in Figs. 2 and 4 of the drawings, this gravel or water-bearing deposit being found usually at a depth varying from ten to eighty feet below the surface of the ground. The inclosing walls of the sheet piling 12 are provided on the side 12^a thereof, and also preferably at the ends 12^b, which walls are directed toward the area from which the supply of water comes, with suitable apertures located opposite to or at the same depth as the deposits of gravel or other water-bearing strata, in order to permit the entrance of the water which normally flows down the valley through said strata, into the inclosed area 13. The direction of flow of water is indicated in Fig. 1 by the numeral 20, in Fig. 2 by the numeral 20^a, and in Fig. 4 by the numerals 20^b and 20^c. These apertures which are cut through the piling are indicated generally in the drawings by the numeral 21, and it will be seen that they are cut in the walls of the inclosure 13, which intercept the free flow of water through the gravel or other water-bearing strata. As shown in the drawings, the alternate piles are provided with apertures 21 in such number as may be necessary to meet the demands of the existing conditions, but each pile can be similarly treated and these are located in any desired number, preferably following the elevation of the water-bearing strata across the ends and upper inlet side of the reservoir. This alternation of the piling to form the apertures 21 is preferably done before the piling is driven into the ground,

although it may be done later, that is, after the piles are driven and after the excavating operation hereinafter referred to.

After finishing the construction above described, the earth in the space 13, within the inclosing walls of sheet-piling 12, is excavated to a depth reaching slightly below the gravel or water-bearing strata, and to a considerably greater depth if the requirements for storage can be better served thereby. The bottom of the reservoir thus formed within the piling 12 is then preferably provided with a floor of concrete 22, which floor resists the lateral pressure on the lower portions of the piling as well as the upward pressure from below, while at the same time facilitating the cleaning of the reservoir and also excluding impurities from mixing with the water, which, as will be well understood, flows in through the apertures 21.

To facilitate the excavation of the earth within the space 12, and to exclude water from flowing in through the apertures 21 during the process of excavation, Z-bars 23 are riveted to each of the alternate piles 18^a, as shown in Fig. 5, before the piling is driven, and these Z-bars serve to retain planks 24, which may be placed against the piles, opposite the apertures 21 so as to substantially close said apertures and prevent the flow of water therethrough in large quantities during the excavation. These planks may also be used temporarily to exclude water from the reservoir at any time when inspection or repairs to the reservoir may be necessary, and they may also be employed to partially stop the flow of water into the reservoir, if such stoppage of the flow is desired.

The apertures in the piling, indicated generally by the numeral 21, preferably consist of a plurality of bell-shaped perforations or apertures 26, which are drilled or cut directly through the webs of the piles and arranged with their larger extremities toward the inner side of the reservoir. It will be seen that these bell-shaped apertures 26 serve to transform a portion of the piles into the form of a screen, and from the nature and arrangement of the apertures 26, above described, it will be seen that they effectually prevent the entrance of large portions of material into the reservoir while at the same time permitting the entrance of substantially filtered water. The shape of the apertures or perforations 26 also permits the screen to be readily cleaned, and prevents said perforations from becoming clogged by finely divided material which may tend to pass therethrough, and which might otherwise clog the openings. In some instances, relatively large openings or apertures may be cut through the piling and screens placed over the openings, the screens

having perforations 26 extending therethrough, of the same form as the perforations which I preferably provide directly through the web of the piling. Fig. 6 shows a sectional view of a pile with the perforations 26 therethrough, or of a screen provided with said perforations.

The collection of water within the reservoir is facilitated by the construction and use of the wing walls 14 which extend to the desired distance across the valley and substantially prevent the continued flow of water down the valley through the water-bearing strata. The water being thus prevented from flowing down the valley by the wing walls 14, and also by the lower wall of the reservoir, flows into my improved reservoir through the opening 21, and since it cannot escape from the reservoir after entering said openings, it wells up under the influence of the head of water up the valley and thus tends to fill the reservoir, as shown clearly in Figs. 2 and 4, where the water is indicated by the numeral 27.

25 The wing walls 14, which are formed of piling driven to a safe penetration below the water-bearing strata of the valley, are constructed with the upper ends of the piling cut off at such depth below the surface of the ground as will permit the free flow of any surface streams and prevent the soaking of the surface soil of the valley above the wing walls in such manner as to destroy its usefulness for agricultural or other purposes, while at the same time operating to effectually dam the flow of water in order to cause the same to well up in the reservoir.

To prevent the entrance of impurities, such as surface water, into the reservoir 40 through the top opening thereof, and also to provide the reservoir with what may be termed a spillway for permitting the escape of the overflow from within the reservoir, in those installations where it may be desired, 45 I provide the inclosing sheet piling 12 of such length that the upper ends of the piles are left projecting a short distance above the surface of the ground 28, as shown at 29, and a levee 30 is formed all around the outside 50 of the inclosing wall of piling, all of which will be well understood from the foregoing description taken with the drawings and appreciated by those skilled in this particular art. It will be seen that this levee 30 prevents the entrance of surface water or other 55 impurities into the reservoir, and at the same time permits an undue accumulation of water within the reservoir to spill over the upper edges thereof and flow down the 60 valley.

While I have shown and described a particular method of constructing a reservoir according to my invention and a particular 65 form of construction, it will be understood that these improvements may be embodied

in various different forms without departing from my invention as defined by the appended claims.

I claim:—

1. The method of constructing a reservoir 70 which consists in driving an inclosing sheet piling into the earth around the desired location, then excavating the earth from the inclosure to a depth short of the bottom of the piling to form a reservoir, then cutting away 75 a portion of the piling near the bottom of the inlet side of the reservoir, and finally inserting a screen over the aperture formed by cutting away said portion of the piling.

2. In reservoirs of the class described, the 80 combination of an inclosing sheet piling driven into the ground to the desired depth and through a gravel bed, said piling being provided with a cut-away portion near the lower portion of the inlet side of said piling 85 opposite the bed of gravel, and a screen covering for said cut-away portion.

3. In reservoirs of the class described, the 90 combination of an inclosing sheet piling driven into the ground the desired depth and through a gravel bed and provided with a cut-away portion near the lower portion of the inlet side of said piling, a screen covering for said cut-away portion, and a levee surrounding the upper portion of said reservoir 95 to provide a spillway.

4. In reservoirs of the class described, an inclosing sheet piling driven into the ground to the desired depth and through a gravel bed, to form an inclosure from which the 100 earth may be excavated to form a reservoir, said piling being provided on the inlet side thereof opposite said gravel bed with a series of perforations extending therethrough, said perforations increasing in 105 cross-section toward the interior of said reservoir.

5. In reservoirs of the class described, the 110 combination of an inclosing sheet piling driven into the ground to the desired depth and through a water-bearing stratum, wing walls formed by driving sheet piling into the ground outwardly of said inclosing piling and downwardly through said water-bearing stratum, said inclosing sheet piling being 115 provided on the inlet side thereof opposite said water-bearing stratum with a plurality of perforations to form a screen.

6. In reservoirs of the class described, the 120 combination of interlocking sheet piling driven into the ground in the desired location in a valley to form an inclosure from which the earth may be excavated, said piling being driven through a water-bearing stratum, and wing walls extending from said 125 inclosure across said valley, said wing walls being formed by interlocking sheet piling driven downwardly through said water-bearing stratum, said inclosing sheet piling being provided with a screen on the inlet 130

side thereof opposite said water-bearing stratum.

7. In reservoirs of the class described, the combination of interlocking sheet piling driven into the ground to the desired depth and through a water-bearing stratum to form an inclosure from which the earth may be excavated, the joints between adjacent piles being substantially water-tight, and

screens in said piling near the lower portion of the inlet side thereof opposite said water-bearing stratum.

In testimony whereof, I have subscribed my name.

JESSE LOWE, SR.
